UNITED STATES PATENT OFFICE.

ALBERT A. PAGE, OF NEW HAVEN, CONNECTICUT, ASSIGNOR TO SARGENT & COMPANY, OF SAME PLACE.

DESIGN FOR A BRACKET FOR MEAT-CUTTERS.

SPECIFICATION forming part of Design No. 21,386, dated March 8, 1892.

Application filed February 1, 1892. Serial No. 419,991. Term of patent 14 years.

To all whom it may concern:

Be it known that I, ALBERT A. PAGE, of New Haven, in the county of New Haven and State of Connecticut, have invented a new Design 5 for a Bracket for Meat-Cutters; and I do hereby declare the following, when taken in connection with accompanying drawings and the letters of reference marked thereon, to be a full, clear, and exact description of the same, 10 and which said drawings constitute part of this specification, and represent, in—

Figure 1, a side view, and Fig. 2 an end view looking from the left of Fig. 1.

This invention relates to a design for that 15 part of a meat-cutter which forms the support, commonly called the "bracket;" and it consists in the shape of the bracket, as described, and shown in the accompanying illustrations.

20 At the end of the case the bracket represents the appearance of a straight arm A, ex-

tending downward from the case B and turned inward at its lower end, as at C. At a point on the case forward of the arm A two downwardly-curved legs D D are represented, the 25 legs being represented as diverging from the case downward, and from the arm A curved branches E E are represented as extending from opposite sides of the said arm forward and as joining the legs D D at their lower end, 30 all as shown in the accompanying illustrations.

I claim—

The design for a bracket for meat-cutters, as herein shown and described. 35

In testimony whereof I have signed this specification in the presence of two subscribing witnesses.

ALBERT A. PAGE.

Witnesses:

ELLIOTT LITTLEJOHN,
FREDERICK A. JACKSON.
